TRASH RECEPTACLE HOOD

Felice Pipolo, 270 Bellingham,
Williamsville, N.Y. 14221

Filed Sept. 23, 1968, Ser. No. 13,669

Term of patent 14 years

Int. Cl. D7—06

U.S. Cl. D49—35

Fig. 1

Fig. 3

Fig. 4

FIGURE 1 is a perspective view of a trash receptacle hood showing my new design;

FIGURE 2 is a perspective view thereof with the access doors in open position;

FIGURE 3 is a top plan view thereof; and

FIGURE 4 is a bottom plan view thereof.

The broken lines in FIG. 1 are shown for illustrative purpose only to illustrate the association of the trash receptacle hood with a trash can.

I claim:

The ornamental design for a trash receptacle hood, as shown and described.
